UNITED STATES PATENT OFFICE.

MARTIN W. ROBINSON, OF MEDFORD, MASSACHUSETTS.

ELECTRIC BATTERY.

SPECIFICATION forming part of Letters Patent No. 705,148, dated July 22, 1902.

Application filed May 11, 1901. Serial No. 59,775. (No model.)

To all whom it may concern:

Be it known that I, MARTIN W. ROBINSON, of Medford, in the county of Middlesex and State of Massachusetts, have invented a new and useful Improvement in Electric Batteries, of which the following, taken in connection with the accompanying drawings, is a specification.

My invention relates to electric batteries; and the principal object of the same is to provide a durable or permanent non-frangible cathode or negative element for galvanic batteries.

The carbon cathodes in common use are liable to be broken in handling if made thin, and if made of a thickness to be strong a free circulation of the bath liquid is impeded to some extent.

In carrying out my invention I form the cathode of a thin copper plate having a number of openings or perforations therein to permit a free circulation of the bath solution, said copper plate being coated with nickel after the openings or perforations have been formed in said plate, so that the entire surface of the cathode exposed to the bath is rendered impervious to the action of the bath solution. Such a cathode may be made comparatively thin and will not be liable to breakage in shipping or handling and may be used in connection with the usual zinc element in a bath composed of the usual constituents; but I prefer to use a bath solution composed of bichromate of soda or a solution of bichromate of soda with sulfuric acid in the proportion of about twenty to one.

In the accompanying drawings, Figure 1 is a perspective view of a battery such as I may use. Fig. 2 is a central vertical section through the positive and negative elements of the battery. Fig. 3 is a perspective view of one of the cathodes made in accordance with my invention. Fig. 4 is an enlarged sectional view of the cathode.

In said drawings the numeral 1 designates a non-conducting cup for containing a bath solution 2, said solution being composed, preferably, of bichromate of sodium or a solution of the same and sulfuric acid in proper proportions. The cathode 3 consists of a copper

plate 4, having a series of openings or perforations 5 therein to permit a free circulation of the bath solution. The copper plate 4 is coated or plated with nickel 6, said nickel being impervious to the action of the bath solution. As shown in the drawings, a series of these nickel-plated copper plates 4 are utilized, and they are connected together by a screw 7, passing through alined apertures 8, formed in ears 9 on the upper ends of the plates. Rings or washers 10 are used to hold the plates the required distance apart, and a thumb-nut 11 fits the threaded end of the screw 7 to bind the plates together. Small buffers 12, made of some impervious or non-conducting material, like vulcanite or vulcanized fiber, are secured in suitable openings in the upper and lower portions of the plates 4, said buffers extending upon opposite sides of the plates 4 to prevent contact of the zinc elements 13 with the cathodes 4. The zinc plates 13 are also secured together by a binding-screw 14, passing through a tubular washer 15 between the plates 13.

It will be understood that any suitable number of the plates 4 and 13 may be alternately disposed in the bath and held out of contact by the buffers 12 and that owing to the fact that the cathodes are comparatively thin very little space is necessary to accommodate quite a large number.

Having thus fully described my invention, what I claim is—

1. A cathode composed of a nickel-plated copper plate, having non-conducting buffers secured thereto in combination with intermediate zinc plates alternately arranged, substantially as described.

2. A cathode composed of perforated nickel-plated copper plates connected together by a binding-screw, and intermediate zinc plates, substantially as described.

3. A galvanic battery consisting of nickel-plated copper cathodes and zinc anodes immersed in a bath composed of bichromate of sodium and sulfuric acid, substantially as described.

4. A galvanic battery consisting of perforated nickel-plated copper cathodes, secured together by a binding-screw, and zinc anodes

secured together by a separate screw and arranged intermediate the cathodes, said elements being immersed in a bath composed of bichromate of sodium and sulfuric acid, substantially as described.

5. The herein-described battery elements, consisting of perforated copper plates coated with nickel and secured together by a binding-screw, and zinc plates located intermediate the copper plates and connected by a screw, and non-conducting buffers for hold-

ing the plates apart, substantially as described.

In testimony whereof I have signed my name to this specification, in the presence of 15 two subscribing witnesses, on this 5th day of April, A. D. 1901.

MARTIN W. ROBINSON.
